HANDBAG

Sidney Hyman, New York, N. Y.

Application February 27, 1953, Serial No. 23,824

Term of patent 3½ years

(Cl. D87—3)

To all whom it may concern:

Be it known that I, Sidney Hyman, a citizen of the United States, residing at New York, in the county of New York and State of New York, have invented a new, original, and ornamental Design for a Handbag, of which the following is a specification, reference being had to the accompanying drawing, forming part thereof.

In the drawing:

Fig. 1 is a front perspective view of a handbag, showing my new design;

Fig. 2 is a rear perspective view of the same, showing one-half of the cover in opened condition; and

Fig. 3 is an end elevational view of Fig. 2.

I claim:

The ornamental design for a handbag, as shown.

SIDNEY HYMAN.
